LEUCO-COMPOUNDS OF VAT DYES

Jean Georges Kern, Wilmington, Del., assignor
to E. I. du Pont de Nemours & Company, Wil-
mington, Del., a corporation of Delaware

No Drawing. Application August 19, 1927,
Serial No. 214,217

33 Claims. (Cl. 260—61)

This invention relates to organic salts of the acidic derivatives of the leuco-compounds of vat colors and more especially to the alkyloamine salts, for example, those produced by the inter-
action of these acidic bodies and di- and tri-
ethanolamine or mixtures of these.

The stabilizing of the leuco-compounds of vat colors has been an object of other inventions because of its importance to the dyeing industry.
10 Methods for producing stable acidic derivatives of the leuco-compounds of vat colors have been patented as described in British Patents Nos. 248,802—245,587—247,787—251,491. These four British patents disclose the treatment of vat dyes
15 of every class, such as, broadly, the indigo, thio-indigo, anthraquinone, benzanthrone and indanthrone vat dyes, and specifically indigo, flavanthrone, indanthrone, anthraquinone-2:1-naphthacridone, di-methoxy-dibenzanthrone, di-
20 chloro-isodibenzanthrone, pyranthrone, nitro-dibenzanthrone, dichlorindanthrone, and the various indigooids and halogenated indigos, such as 4:4'-dichlor-7:7'-dibrom-indigo, 5:5'-dibrom-6:6'-diethoxy-thioindigo, 5:5'-7:7'-tetra-brom-
25 indigo, and, in fact, any vat dye. The leuco form of these vat dyes reacts to form esters with acidic compounds, and preferably polybasic acid compounds such as alkyl sulphuric acid halides, phosphorus oxy-chloride, alkyl phos-
30 phoric dichlorides, chlorosulphonic acid, sulphuric anhydride, fuming sulphuric acid, and salts of pyro-sulphuric acid. It is with such esters of leuco vat dyes that my invention is concerned.

These acidic compounds and others derived
35 from the leuco-compounds by the action of the chlorides of phosphorus and of chlor-acetic acid are water soluble by reason of the fact that they form sodium and potassium salts. When submitted to oxidation they revert to the vat color
40 in its insoluble form. The vat colors of the present invention contain a ketone group. This ketone group on reduction with hydrosulfite and caustic is converted into the group

45
$$-\text{O}-\text{OH}$$

This, in turn, in the presence of the caustic soda, forms the sodium salt

50
$$-\text{O}-\text{ONa}$$

which is soluble and acts as the dye. It will be apparent that if this sodium salt could be stabilized, it would be unnecessary to perform the reduction every time the step of dyeing is carried

out, and moreover, it could be used in the absence of alkali.

However, this leuco compound containing the grouping

is so extremely unstable that it oxidizes instantly when the reducing agent is removed, giving rise to the original vat color. If the leuco compound containing the grouping

is made and freed from reducing agent in the absence of air and in the presence of an organic base such as pyridine or dimethylaniline, it is possible to remove all the water necessary for the reduction without oxidizing the compound. When the water-free mixture of the sodium salt of the leuco compound and chlorosulfonic acid are brought together the sulfonic acid group takes the place of the sodium, resulting in a reaction most probably represented by the following general equation:

I have found that when an organic base containing hydroxyl groups and represented by the general formula given below is substituted for the sodium in the acidic esters of the leuco-compounds referred to above, the resulting product has distinct advantages because of the surprising fact that these esters are much more soluble and dissolve better than the alkali salts. In fact, by their use one can overcome the great objection to the acidic derivatives at present in commerce that they do not keep well and show an increasing insolubility. For this purpose, it is possible to use bases of the following general type:

where Alk represents an aliphatic or hydroxy aliphatic radical, R₁ and R₂ represent hydrogen or an aliphatic radical or a hydroxy aliphatic radical or a poly-hydroxy aliphatic radical.

The sodium salts of the sulfuric acid esters of vat leuco-compounds in the form of pastes are commercial dyestuffs known in the trade under

the name of Indigosol or Soledon colors. These esters have the disadvantage, however, of not being very stable and not being as soluble as may be desired in dyes of this kind.

5 In making my new soluble forms I may proceed as follows:

The sodium salt of the sulfuric acid ester of the vat leuco-compound in the form of a paste is treated with a suitable organic acid. This results in the precipitation of the free sulfuric ester of the vat leuco-compound. This acid is separated and then dissolved by the addition of a mixture of di- and triethanolamine. The following procedure may be used in carrying out 10 my invention, but it is to be understood that this is illustrative only and is not to be taken as a limitation of my invention.

One thousand parts of the dye known as Soledon jade green paste are poured into a beaker and 20 1000 parts of water are added. To the resulting liquid a 20% acetic acid solution is added slowly, with stirring, until the reaction becomes acid, the temperature being maintained between 20° C. and 25° C. The free leuco sulfuric acid ester 25 precipitates. It is then filtered off quickly, and rinsed with a little water until the filtrate is neutral. The filter cake is pressed as far as possible to free it from moisture. To 250 parts of the filter cake are added 250 parts of di-ethanolamine.

It may be stated that the addition of acetic acid gives a leuco-sulfuric ester because an equilibrium is set up, the free sulfuric ester being formed. This may be represented by the following general equation:

40 The dye dissolves and the concentration of the thick pasty material is twice that of the original dye. It is preferable to conduct the operation in the absence of oxygen, but this is not absolutely necessary.

45 The quantity of ethanolamine used may be varied, as also the quantity of water in the product, without altering the condition. Mono-ethanolamine or tri-ethanolamine or methyl-di-propane-diol-amine may be substituted in the 50 example given, and similar results obtained. Instead of the dye mentioned any of the soluble acidic derivatives may be used.

Instead of preparing the organic salt in this 55 way, a similar result may be obtained by adding the organic base to a printing paste in which the soluble acidic derivative of the leuco-vat color is used. For instance, a printing paste made with 100 parts of the commercial soluble acidic derivative of any of the vat leuco-compounds mixed 60 with 80 parts of one of the bases mentioned above and 820 parts of British gum starch thickening may be printed in the ordinary way either on cotton, silk or wool. After printing, the goods are aged from four to five minutes in the usual 65 manner, passed into an oxidizing bath containing either ferric chloride or sodium nitrite and sulfuric acid or ammonium persulfate.

70 It is not necessary to isolate the free acid derivative of the vat color leuco-compound to obtain a more soluble product. The direct addition of the organic bases described to the commercial dyes apparently causes a formation of compounds of higher solubility, or acts merely as a solvent. 75 In any event, the solution is rendered much

better and the tendency to precipitate is lessened very greatly.

As many apparently widely different variations of this invention may be made without departing from the spirit thereof, it is to be understood that I do not limit myself to the foregoing examples or description except as indicated in the following patent claims.

I claim:

1. The process of producing alkylolamine salts of inorganic sulphur and phosphorus acidic esters of leuco-vat dyes, which comprises combining the acidic ester with an alkylolamine. 85

2. The process of producing alkylolamine salts of inorganic sulphur and phosphorus acidic esters of leuco-vat dyes, which comprises combining the acidic ester with an ethanolamine. 90

3. The process of producing alkylolamine salts of inorganic sulphur and phosphorus polybasic-acid esters of leuco-vat dyes, which comprises combining the acidic ester with an alkylolamine. 95

4. The process of producing alkylolamine salts of inorganic sulphur and phosphorus polybasic-acid esters of leuco-vat dyes, which comprises combining the acidic ester with an ethanolamine. 100

5. The process of producing alkylolamine salts of inorganic sulphur and phosphorus polybasic-acid esters of leuco-vat dyes, which comprises combining the acidic ester with triethanolamine. 105

6. The process of producing alkylolamine salts of inorganic sulphur and phosphorus polybasic-acid esters of leuco-vat dyes, which comprises treating an alkali metal salt of the said ester with an organic acid and thereafter treating the mixture with an alkylolamine. 110

7. The process of producing alkylolamine salts of inorganic sulphur and phosphorus polybasic-acid esters of leuco-vat dyes, which comprises treating a sodium salt of the said ester with acetic acid and thereafter treating the mixture with an alkylolamine. 115

8. The process of producing alkylolamine salts of inorganic sulphur and phosphorus polybasic-acid esters of leuco-vat dyes, which comprises treating a sodium salt of the said ester with acetic acid and thereafter treating the mixture with a mixture of di- and triethanolamines. 120

9. The process of producing an alkylolamine salt of a sulphuric acid ester of a leuco-vat dye, which comprises combining the ester with an alkylolamine. 125

10. The process of producing an alkylolamine salt of a sulphuric acid ester of a leuco-vat dye, which comprises combining the ester with an ethanolamine.

11. The process of producing an alkylolamine salt of a sulphuric acid ester of a leuco-vat dye, which comprises combining the ester with a mixture of di- and triethanolamine. 130

12. The process of producing an alkylolamine salt of a sulphuric acid ester of a leuco-vat dye, which comprises treating the sodium salt of the said ester with acetic acid and thereafter treating the mixture with an alkylolamine. 135

13. The process of producing an alkylolamine salt of a sulphuric acid ester of a leuco-vat dye, which comprises treating the sodium salt of the said ester with acetic acid and thereafter treating the mixture with an ethanolamine. 140

14. The process of producing an alkylolamine salt of a sulphuric acid ester of a leuco-vat dye, which comprises treating the sodium salt of the said ester with acetic acid and thereafter treating the mixture with a mixture of di- and triethanolamines. 145

15. As new products, the alkylolamine salts of inorganic sulphur and phosphorus acidic esters of leuco-vat dyes.	
16. As new products, the ethanolamine salts of inorganic sulphur and phosphorus acidic esters of leuco-vat dyes.	
17. As new products, a mixture of di- and tri-ethanolamine salts of inorganic sulphur and phosphorus acidic esters of leuco-vat dyes.	
10 18. As new products, the alkylolamine salts of inorganic sulphur and phosphorus polybasic-acid esters of leuco-vat dyes.	80
15 19. As new products, the ethanolamine salts of inorganic sulphur and phosphorus polybasic-acid esters of leuco-vat dyes.	85
20 20. As new products, a mixture of di- and tri-ethanolamine salts of inorganic sulphur and phosphorus polybasic-acid esters of leuco-vat dyes.	90
20 21. As new products, the alkylolamine salts of sulphuric acid esters of leuco-vat dyes.	95
22. As new products, the ethanolamine salts of sulphuric acid esters of leuco-vat dyes.	
23. As new products, a mixture of di- and tri-ethanolamine salts of sulphuric acid esters of leuco-vat dyes.	
25 24. The process of producing alkylolamine salts of acidic esters of leuco vat colors which comprises combining an alkylolamine with an acidic ester of a leuco vat color selected from the group consisting of inorganic sulphur and phosphorus acidic esters of the indigo, thioindigo, anthraquinone, benzanthrone and indanthrone series.	100
30 25. The process of producing alkylolamine salts of acidic esters of leuco vat colors which comprises combining an alkylolamine with an ester resulting from the esterification of a leuco vat color with an acidic compound selected from the group consisting of alkyl-sulphuric acid halides, phosphorus-oxy-chloride, alkyl-phosphoric di-chlorides, chlor-sulphonic acid, sulphuric-anhydride, fuming-sulphuric acid, salts of pyro-sulphuric acid and chlor-acetic acid.	105
40 26. The products obtained by combining an alkylolamine with an acidic ester resulting from the esterification of a leuco vat color selected from the group consisting of indigo, thio-indigo, anthraquinone, benzanthrone and indanthrone vat colors with an esterifying agent selected from the group consisting of alkyl-sulphuric acid halides, phosphorus-oxy-chloride, alkyl-phosphoric di-chlorides, chlor-sulphonic acid, sulphuric-anhydride, fuming-sulphuric acid, salts of pyro-sulphuric acid and chlor-acetic acid.	110
